DESIGN FOR A ROLLER SKATE

John S. Coldwell, Milwaukee, Wis., and Walter F. Nessen, Oak Park, Ill., assignors to Globe-Union Inc., Milwaukee, Wis., a corporation of Delaware

Application April 26, 1940, Serial No. 91,972

Term of patent 7 years

To all whom it may concern:

Be it known that we, John S. Coldwell and Walter F. Nessen, both citizen of the United States, residing at Milwaukee, in the county of Milwaukee and State of Wisconsin, and at Oak Park, in the county of Cook and State of Illinois, respectively, have invented a new, original, and ornamental Design for a Roller Skate, of which the following is a specification, reference being had to the accompanying drawing forming a part thereof, and in which:

Figure 1 is a top plan view of a roller skate showing our new design;

Figure 2 is a view thereof in side elevation; and

Figure 3 is a view thereof in end elevation.

We claim:

The ornamental design for a roller skate, as shown.

JOHN S. COLDWELL.
WALTER F. NESSEN.
